UNITED STATES PATENT OFFICE.

GEORGE F. HALL, OF NEWARK, NEW JERSEY, ASSIGNOR OF ONE-HALF TO
ELLIS R. CARHUFF, OF SAME PLACE.

DESIGN FOR A ROCKING-CHAIR BASE.

SPECIFICATION forming part of Design No. 19,693, dated March 11, 1890.

Application filed January 6, 1890. Serial No. 336,086. Term of patent 7 years.

To all whom it may concern:

Be it known that I, GEORGE F. HALL, a citizen of the United States, residing at Newark, Essex county, New Jersey, have invented a certain new and useful Design for a Rocking-Chair Base, fully described and represented in the following specification and the accompanying drawing, forming a part of the same.

This invention relates to a design for the base of that class of rocking-chairs comprising a chair-seat suspended by means of links from a stationary base, and more particularly to a special shape for the two sides of such a chair-base connected together by cross-pieces.

a a are the sides of the base, provided with projections *b b'* near the ends of its upper edge. Such sides are formed with an outline of elongated form, their length being considerably greater than their depth, and the depth of each at the forward end having the projec-

tion *b* being greater than that at the opposite end provided with the projection *b'*. Each of the sides *a a* is formed with parallel-sided slots *s s'*, inclined toward one another and concentric, respectively, with the projections *bb'*. 25

What I claim herein is—

The design for a rocking-chair base, which consists in an outline of elongated form, of greater depth at the front than at the rear, and two curved parallel-sided slots inclined 30 upwardly toward each other within such outline, substantially as herein set forth.

In testimony whereof I have hereunto set my hand in the presence of two subscribing witnesses.

GEORGE F. HALL.

Witnesses:

THOS. S. CRANE,
HENRY J. MILLER.
